Patented Dec. 23, 1919.

UNITED STATES PATENT OFFICE.

GEORGE ALBERT LYON, OF PHILADELPHIA, PENNSYLVANIA.

ADJUSTABLE AUTOMOBILE-BUFFER.

1,325,741.

Specification of Letters Patent. Patented Dec. 23, 1919.

Application filed June 12, 1919. Serial No. 303,550.

To all whom it may concern:

Be it known that I, GEORGE ALBERT LYON, a citizen of the United States, and resident of Philadelphia, county of Philadelphia, 5 and State of Pennsylvania, have made a certain new and useful Invention Relating to Adjustable Automobile-Buffers, of which the following is a specification, taken in connection with the accompanying drawing.

10 This invention relates to resilient automobile buffers preferably formed of spring steel strip and having a front or impact receiving portion reinforced by or more or less composed of flanged spring steel strip 15 so as to have a desirable alining action on the coöperating connecting portions of the other members of the buffer. The attaching members of the buffer adapted to be clamped or otherwise secured to the frame 20 of the automobile or other vehicle may be formed with end loops or curved resilient portions and may in some cases extend inward more or less toward each other, and the flanged spring steel strip which preferably forms the front of the buffer may in some cases be outwardly bowed or arched throughout its central portion and may be bolted or clamped to the connecting portions of the other buffer members so as to 25 form substantially vertically rigid connection therewith and constitute a reinforcement therefor in some cases. The form of connecting devices used may be such as to permit the width of the buffer and the distance between its attaching members to be 30 adjusted so as to fit automobiles having frame members located at different distances apart and the alining flange on the front buffer member may advantageously be arranged on the top edge thereof so as to more or less conceal the coöperating connecting portions of the other buffer members. This 35 application is a continuation in part of my co-pending application, Serial No. 215,761, filed February 7, 1918, and contains subject-matter taken therefrom, said prior application more specifically claiming the Figure 1 form of buffer with one or more reinforcing strips.

40 In the accompanying drawing showing in a somewhat diagrammatic way illustrative embodiments of this invention,

Fig. 1 is a top view of one form of buffer.

45 Fig. 2 is a diagrammatic perspective view showing the different parts in separated position.

Fig. 3 is a transverse sectional view taken substantially along the line 3—3 of Fig. 1.

Fig. 4 is a top view of another form of 60 buffer partly in section.

Fig. 5 is an enlarged transverse section thereof taken substantially along the line 5—5 of Fig. 4.

Fig. 6 is an enlarged sectional view taken substantially along the line 6—6 of Fig. 4; 65 and

Fig. 7 is a top view showing still another form of buffer partly in section.

The buffer shown in Figs. 1 to 3 may be composed of a number of strips of resilient 70 material such as tempered spring steel and it is desirable to have these strips, at least throughout such portions as are subject to considerable vertical bending forces, given a considerably greater vertical width 75 than thickness so as to make them vertically rigid while resiliently yielding to a much greater extent in horizontal directions to absorb collision impacts. Two such strips are shown in Figs. 1 and 2 as having practically 80 similar contour and comprising attaching members of any suitable shape and construction to be connected to the automobile frame or other part of the vehicle. One of these strips may as indicated comprise the attaching member 1 and the transversely extending impact receiving member 3 which may be connected by any suitably curved resilient portion, such, for example, as the interposed open end loop 2 which is adapted to extend 85 outward into protective position adjacent the automobile wheel. The other similar spring strip member comprises the attaching member 4, the resilient end loop 5 and the impact receiving member 6 which in the 90 assembled buffer is preferably arranged substantially in line with the other impact receiving member and adjustably supported or held in connection therewith.

95 For this purpose one or more flanged reinforcing connecting members preferably of a resilient character may be clamped or bolted by any suitable connecting devices to the coöperating inner ends or connecting portions of the impact receiving members. 100 Such reinforcing members may be advantageously formed of spring steel strip which has been rolled or formed with a narrow alining flange or portion and may be arranged on either side of the impact receiving members and extend any desired distance along the same so as to simultaneously 105 110

connect the same and form a multiple thickness reinforced front portion of the buffer which may advantageously extend at least throughout the distance between the attaching members or automobile frame members to which they are connected. As indicated in the drawing the resilient reinforcing member 7 which may be of spring steel strip may be securely connected or clamped on the front side of the impact receiving members as by suitable connecting devices or bolts 9, 10 which may extend through square or polygonal connecting openings or holes 14, 15 in this flanged reinforcing member and may, if desired, be provided with square or polygonal shank portions 15 to engage these connecting holes and thereby prevent undesirable rotation of the bolts with respect to this front member. The connecting bolts may extend through suitable adjusting connecting openings in the impact receiving members to allow their lateral adjustment, and for example these connecting bolts may extend through any one of the series of adjusting connecting holes 16, 17 in one or both of the impact receiving members of the other buffer strips. In this way sufficient relative adjustment of width of the buffer and the distance between its attaching members can be secured so as to cover the extreme range of width in the usual commercial automobile frames and at the same time by having a single bolt hole in the front reinforcing member within which the connecting bolt fits rather closely the parts are more or less prevented from moving or working loose under running conditions.

As indicated in Figs. 1 and 3 the connecting bolts may with advantage be formed with rounded heads so as to have a neat and finished appearance in connection with the front reinforcing or flanged resilient member of the buffer which like the bolt heads may be nickel plated, if desired. One or more nuts 11 may be arranged on each of the bolts and lock washers or other retaining devices 12 may be employed, if desired. Additional vertical rigidity may be given to the connection between the co-operating buffer members by the vertical alining flange, such as 13, on the reinforcing member which as indicated in Fig. 3 may more or less overlap the adjacent portions of the impact receiving members and be tightly held in connection therewith by the connecting bolts or devices so as to minimize or prevent undesirable vertical movement between these parts; also by arranging this relatively narrow alining flange at the top of the front or reinforcing member of the buffer it may serve to substantially conceal the opening between the inner ends of the impact receiving members of the buffer. Such reinforcing members may like the

other buffer strips be formed with the usual rounded edges indicated in Fig. 3 which give a more pleasing appearance to the device and the alining flange may of course be formed when the spring steel strip is originally rolled or by subsequently bending over one edge of such a reinforcing member before it is hardened and tempered.

Such a flanged reinforcing or front member of the buffer may in some cases extend out considerably farther than is indicated in Fig. 1 and may indeed in some cases advantageously constitute the front or impact receiving member of the buffer to which the other buffer strips or members may be clamped, bolted or otherwise secured and constitute doubled or reinforced strength portions of greater or less extent in connection therewith. As shown in Figs. 4 and 5, the flanged impact receiving or buffer front member 23 which may be of tempered spring steel or other resilient material may be originally rolled with a narrow flange 26 which considerably stiffens the buffer member and also constitutes a vertical alining flange or portion, facilitating the vertical alinement of the other buffer members which may be clamped or bolted thereto. This flanged impact receiving member 23 may be of arched or forwardly curved form at least throughout its central portion, and for some purposes it is desirable to have the end connecting portions 24, 25 with which the other buffer members co-operate formed substantially straight so that adjustment of these co-operating connecting portions, such as 22, of the attaching members 20 need not throw these attaching members out of parallelism to even a slight extent. These attaching members which may be formed of resilient strips such as tempered spring steel preferably having considerably greater vertical width than thickness may advantageously be provided with a resilient loop such as 21 adjacent the connecting portion 22 of these buffer members which may be adjustably or otherwise connected to the resilient front or impact receiving member of the buffer by any suitable clamping or connecting devices, such as clips 27 one or more of which may extend around these members as indicated in Fig. 5 and securely connect them when the bolt 28 passing through the ends 29 of this clamp or clip is tightened. For this purpose the nut 30 and lock washer 31 may be provided so that subsequent loosening of the parts is prevented. The alining flange may advantageously be formed with a somewhat angular alining face 46 as shown in Fig. 5 so that when the co-operating connection portions or strips 22 are clamped or bolted against this flanged impact receiving or front member their alinement is secured by engagement at this point and at the opposite edge 47 of the connection portion 22. If

desired also these connecting portions 22 may be slightly downwardly curved or bent so that as shown in a somewhat exaggerated way in Fig. 6 these connecting portions tend 5 to engage the alining flange at two separated points, such as 42, 43, while the intermediate portion 32 of this connecting portion is slightly out of contact at least until the parts are forced home by the engagement of 10 the clamping or connecting device 27 with the free edge 47 of this connecting portion. In this way and by forcing the flat coöperating faces of these resilient strips or members together strong and reliable connection with 15 the buffer elements is secured combined with convenient adjustment of the parts so as to adjust the distance between the attaching members, such as 20, of the buffer to fit automobile frames of different width. The 20 use of such a narrow alining flange on at least the outer edge of the front or impact receiving member of the buffer gives a pleasing appearance thereto as well as reinforcing the resilient yielding action of this buffer 25 member and when mounted on an automobile the connecting portions 22 of the attaching members are practically concealed so as not to undesirably interfere with the pleasing contour of the device.

30 Fig. 7 shows another illustrative construction in which a flanged impact receiving member 33 preferably of resilient material such as tempered or other spring steel strip may be formed with an alining flange 34 against which the connecting portions of the 35 other buffer members may be clamped or bolted in any suitable way. The attaching members 35, 41 of the buffer may as illustrated be provided with end connecting portions, such as 36, which may be formed with 40 one or more connecting slots or openings 37 to receive the shank of the connecting bolt 38 which may securely clamp the parts in adjusted position in connection with the nut 45 40 and lock washer 39, if desired. These connecting bolts may be formed with rounded heads nickel plated or otherwise finished in conformity with the front face of the impact receiving member of the buffer, if desired. The use of such flanged spring steel 50 resilient front members gives a very efficient resilient cushioning action to the buffer under collision conditions so that a considerable collision impact can be resiliently absorbed 55 without breaking or permanently deforming the buffer members and as indicated in Fig. 7 the flanged resilient front member may advantageously extend out to a sufficient distance to protect the wheels of the vehicle if desired and may be given a more or less uniform forwardly arched or curved contour.

This invention has been described in connection with a number of illustrative embodiments, forms, proportions, parts, ar-

rangements, materials, methods of connection and use, to the details of which disclosure the invention is not of course to be limited, since what is claimed as new and what is desired to be secured by Letters Patent is set forth in the appended claims. 65 70

I claim—

1. The automobile buffer comprising a resilient impact receiving front member having considerably greater width than thickness and formed of tempered spring steel 75 strip and having on its upper edge a narrow alining flange having an angularly arranged rear face, said front member having a forwardly arched central portion and substantially straight end connecting portions, attaching members of spring steel strip having resilient loop portions and connecting portions adapted to engage the alining flange of the connecting portions of said front member at separated points and clamping 80 connecting devices to adjustably and substantially rigidly connect said connecting portions and adjust the distance between the rear portions of said attaching members. 85

2. The automobile buffer comprising a resilient impact receiving front member having considerably greater width than thickness and formed of tempered spring steel strip and having on its upper edge a narrow alining flange, attaching members of spring 90 steel strip having resilient loop portions and connecting portions adapted to engage the alining flange of the connecting portions of said front member at separated points and connecting devices to adjustably and substantially rigidly connect said connecting portions and adjust the distance between the rear portions of said attaching members. 95

3. The automobile buffer comprising a resilient impact receiving front member having considerably greater width than thickness and formed of spring steel strip and having on its upper edge a narrow alining flange, attaching members of spring steel strip having resilient portions and connecting portions adapted to engage the alining flange of the connecting portions of said front member and connecting devices to adjustably connect said connecting portions and adjust the distance between the rear 100 portions of said attaching members. 105

4. The automobile buffer comprising a flanged resilient impact resisting member having considerably greater width than thickness extending substantially throughout the buffer front and having on one edge an alining flange, said member having a forwardly arched central portion and substantially straight end connecting portions, attaching members of steel strip having resilient loop portions and connecting portions adapted to engage the alining flange of the connecting portions of said impact 110 115 120 125

resisting member at separated points and clamping connecting devices to adjustably and substantially rigidly connect said connecting portions and adjust the distance between the rear portions of said attaching members.

5. The automobile buffer comprising a flanged resilient impact resisting member having considerably greater width than thickness extending substantially throughout the buffer front and having on one edge an alining flange, attaching members of steel strip having resilient loop portions and connecting portions adapted to engage the alining flange of the connecting portions of said impact resisting member at separated points and connecting devices to substantially rigidly connect said connecting portions.

6. The automobile buffer comprising a flanged resilient impact resisting member having considerably greater width than thickness extending substantially throughout the buffer front, attaching members having resilient loop portions and connecting portions adapted to engage the flanged connecting portions of said impact resisting member and connecting devices to substantially rigidly connect said connecting portions.

7. The automobile buffer comprising a flanged resilient impact resisting member of tempered spring steel having considerably greater width than thickness extending substantially throughout the buffer front, attaching members having resilient curved portions and connecting portions adapted to engage the flanged connecting portions of said impact resisting member and connecting devices to substantially rigidly connect said connecting portions.

8. The automobile buffer comprising a forwardly bowed impact receiving front member having considerably greater width than thickness extending more than three quarters across the buffer and formed of resilient spring steel strip and having connecting portions formed adjacent one edge with an alining flange, attaching members of resilient spring steel strip having curved portions and connecting portions adapted to lie behind and engage the alining flange of the connecting portions of said front member at separated points and connecting devices to adjustably and substantially rigidly connect said connecting portions and adjust the dis-

tance between the rear portions of said attaching members.

9. The automobile buffer comprising a forwardly bowed front member having considerably greater width than thickness extending more than three quarters across the buffer and formed of resilient spring steel strip and having connecting portions formed adjacent one edge with an alining flange, attaching members of resilient spring steel strip having curved portions and connecting portions adapted to lie behind and engage the alining flange of the connecting portions of said front member and connecting devices to substantially rigidly connect said connecting portions.

10. The automobile buffer having a resilient impact receiving front member extending substantially across the buffer and consisting of a tempered spring steel strip and having on one edge an alining flange, said front member having a forwardly arched central portion and substantially straight end connecting portions, attaching members of resilient spring steel strip having outwardly extending resilient loops adjacent the ends of the buffers and connecting portions adapted to engage the alining flange of the connecting portions of said front member at separated points and connecting devices to substantially rigidly connect said connecting portions.

11. The automobile buffer having a resilient impact receiving front member extending substantially across the buffer and consisting of a tempered spring steel strip and having on one edge an alining flange, attaching members having outwardly extending resilient loops adjacent the ends of the buffer and connecting portions adapted to engage the alining flange of the connecting portions of said front member and connecting devices to connect said connecting portions.

12. The automobile buffer having a resilient impact receiving front member and consisting of a tempered spring steel strip and having on one edge an alining flange, attaching members having resilient portions and connecting portions adapted to engage the alining flange of the connecting portions of said front member and connecting devices to connect said connecting portions.

GEORGE ALBERT LYON.
